UNITED STATES PATENT OFFICE.

CHARLES RUSSELL LANG, OF CATHCART, GLASGOW, SCOTLAND, ASSIGNOR TO G. & J. WEIR, LIMITED, OF GLASGOW, SCOTLAND.

STEAM-CONDENSING AND FEED-WATER SYSTEM FOR STEAMSHIPS.

1,377,080.

Specification of Letters Patent.

Patented May 3, 1921.

Application filed July 17, 1919. Serial No. 311,588.

To all whom it may concern:

Be it known that I, CHARLES RUSSELL LANG, a subject of the King of Great Britain and Ireland, residing at Cathcart, 5 Glasgow, Scotland, have invented certain new and useful Improvements in Steam-Condensing and Feed-Water Systems for Steamships; and I do hereby declare the following to be a full, clear, and exact description of the invention, such as will 10 enable others skilled in the art to which it appertains to make and use the same, reference being had to the accompanying drawings, and to letters or figures of reference 15 marked thereon, which form a part of this specification.

This invention relates to steam condensing and feed water systems for steamships in which the water of condensation is withdrawn from the main condenser by a hot-well pump directly driven by a steam engine: the pump delivers the water into the main feed pipe and thence to the suction of the boiler feed pump under a pressure 20 considerably above atmosphere; the steam supply to the pump engine is controlled by a float in a chamber which may be a well at the bottom of the condenser and which receives the water of condensation.

30 In many installations—especially in warships—it is impossible to so arrange the hot-well pump with respect to the condenser that the water supplied to the pump has any considerable head; and consequently, unless 35 the suction valves of the pump are very light and can be opened with very little effort, there is difficulty in filling the pump cylinder with water on the suction stroke of the pump.

40 The present invention—which will be described in the following specification and more particularly defined in the annexed claims—consists in a combination of elements in a system as above mentioned, including a steam-jet ejector placed between the condenser and the hot-well pump for the purpose of maintaining a head on the water supplied to this pump. The head produced by the ejector may be many times 45 greater than the static head due to the vertical distance between the water level in the condenser and the pump, and therefore allows of the condenser being placed low 50 down in the ship, while it enables the pump

to deliver the feed water along the main 55 feed pipe at a greater pressure—it may be a very much greater pressure—than would otherwise be possible, and, moreover, permits of the employment of heavier, and consequently more durable, valves. Further, 60 the provision of a head on the water delivered to the pump allows the latter to receive the water without trouble at a higher temperature than would otherwise be possible or satisfactory.

65 The accompanying drawing illustrates how the invention can be conveniently carried into effect.

70 *a* is the condenser, *m* the float chamber (which receives the water of condensation), and *c* the steam-driven direct-acting hot-well pump. The float *f* in the float chamber acts through the agency of the lever *h*, link *k*, and lever *j* on the valve *d* which controls the supply of actuating steam to 75 the engine *e* which drives the pump *c*. In accordance with the present invention a steam-jet ejector *b* is placed between the float chamber *m* and the pump *c*; the ejector receives the water from the chamber *m* 80 through a non-return valve *g* and delivers it to the pump *c* through the conduit *p*. Steam is supplied to the ejector at *n*.

85 Either live or exhaust steam at any suitable pressure may be employed as the actuating fluid in the ejector; and the ejector may be either single-stage or multi-stage.

Having thus described my invention, what I claim as new and desire to secure by Letters Patent is:—

90 In a steam condensing and feed water system for steamships, the combination with a condenser having a collecting chamber, a main feed pipe, a steam-driven direct-acting pump positioned below the condenser 95 and adapted to discharge the water of condensation from the said condenser into the said main feed pipe, of a steam-jet ejector for discharging the water of condensation from the said condenser to the said pump 100 and placed between the said condenser and the said pump for increasing the pressure above the pressure due to the height of the column leading from the ejector to the condenser.

105 I hereby sign my name to this specification.

CHARLES RUSSELL LANG.
